CLARK W. PARKER, OF FULTON, NEW YORK, ASSIGNOR, BY MESNE ASSIGNMENTS, TO
JAMES H. DUNN, OF SPRINGFIELD, MASSACHUSETTS.

RETARDING MEANS.

1,177,134.

Specification of Letters Patent. Patented Mar. 28, 1916.

Application filed May 24, 1912. Serial No. 699,382.

To all whom it may concern:

Be it known that I, CLARK W. PARKER, of Fulton, in the county of Oswego and State of New York, have invented a certain new and useful Retarding Means, of which the following is a specification.

This invention has for its object a retarding means which is particularly simple in construction, is highly efficient in use, and 10 is particularly applicable to retard the engaging action of the main or disk clutches of motor vehicles, and the invention consists in the combinations and constructions hereinafter set forth and claimed.

15 In describing this invention reference is had to the accompanying drawing in which like characters designate corresponding parts in all the views.

20 Figures 1 and 2 are vertical sectional views, taken at a right angle to each other, of my retarding device.

This retarding device or dash pot comprises, generally, a body 1 formed with a piston chamber 2, a piston 3 movable in the 25 piston chamber, and means for actuating the piston including a part carried by the body 1.

The body 1, in addition to the piston chamber 2, is also formed with a recess 4 30 on one side thereof, which opens into the piston chamber 2 with a slot-like entrance extending lengthwise of the piston chamber, the upper and lower walls of the recess diverging toward the chamber and the upper 35 wall of the recess terminating near the top of the chamber. The slot-like entrance of the recess thus extends from substantially the top of the piston chamber and is of a length materially greater than the length or 40 diameter of the opposite or smaller end of the recess. Said body is also formed with a by-pass 5 extending lengthwise thereof and opening at 6 into the lower end of the piston chamber 2, and terminating short of 45 the top of the chamber, the by-pass conveying the retarding fluid, as oil, from the lower side, to the upper side, of the piston during the downward movement thereof. The by-pass is controlled by means of a needle valve 50 7 carried by the removable top plate 8 of the body 1, the needle valve extending through the top plate and having its inner end coact-

ing with the upper end of the by-pass 5; and its upper end provided with a head or handle 9 by means of which the valve can be 55 adjusted to open or close the by-pass, more or less.

The body, as here shown, comprises the removable top plate 8 and a main shell constituting the bottom and side walls of the 60 piston chamber and the inclosing walls of the recess 4, and of the by-pass 5 and the additional by-pass 12 presently described.

As here shown, the needle valve is 65 threaded at 10 and coacts with a threaded passage in the top plate 8, and is held in its adjusted position by means of a spring-pressed detent 11 mounted on the top plate and coacting with the notched periphery of the head 9. Usually the body 1 is also 70 formed with an additional by-pass 12 which communicates with the upper portion of the chamber 2, it being here shown as directly beneath the recess 4 and as opening at its upper end into the lower portion of the recess 4 and 75 hence in open communication at all times with the upper portion of the piston chamber 2. The by-pass 12 communicates with the chamber 2 through a port 13 opening into the piston chamber between the ends 80 thereof in position to be closed by the piston 3 before the same has completed its downward movement.

The body 1 is supported in any suitable manner, and is here shown as formed with 85 a bracket 14 by which it may be secured to any suitable support as the case of the transmission gearing of a motor car.

The piston 3 is formed with a passage 15 therethrough for permitting the liquid to 90 pass from one side, to the other, of the piston, the passage 15 being controlled by a spring-pressed valve 16 carried by the piston and held to its seat by a spring 17, the valve 16 being arranged to close during the 95 movement of the piston in one direction, as downwardly, and to open against the action of its spring 17 during the movement of the piston upwardly, in order to permit the liquid to flow freely from the upper side of 100 the piston to the lower.

The removable top plate 8 is formed with an inlet 18 for the retarding fluid, as oil, and the chamber 2 is also formed with an

outlet at its lower end alined with the passage 6, the inlet and outlet being closed by plugs 19, 20 respectively.

- The means for actuating the piston comprises a rock shaft 21 extending crosswise of the recess 4 and journaled in one of the side walls thereof near the smaller end or apex of the recess, the rock shaft being spaced apart from the piston chamber, and 10 a rock arm 22 mounted on the rock shaft within the recess, the free end of the rock arm extending through the slot-like entrance of the recess into the chamber 2 and being connected to the piston by means of a link 15 or links 23, and an intermediate portion of the rock arm being movable lengthwise of the slot-like entrance of the recess in the arc materially longer than the diameter of the smaller end of the recess.
- 20 The rock shaft 21 may be actuated in any suitable manner and is usually actuated by the foot lever of the motor vehicle, which lever usually controls the engagement of the friction or disk clutch of the vehicle. The 25 retarding device here illustrated is arranged to retard the engaging action of the clutch by its spring in order to effect a certain sequence of movements or operations of the clutch.
- 30 In operation, the piston 3 is normally in its position near the lower end of the piston chamber 2 into which it has been drawn by the spring of the clutch of the vehicle. During the upward movement of the piston 35 3 from its position shown in Figs. 1 and 2, which movement of the piston is effected by the foot pedal of the motor vehicle, the valve 16 opens so that the piston offers a minimum resistance. When, however, the pedal is released and the main spring of the clutch of the vehicle tends to throw the disks into engagement and to move the piston downwardly, the resistance at first is somewhat less than the maximum resistance, as both 40 45 by-passes are open. During such downward movement of the piston, the clutch disks are permitted by the retarding device to lightly engage, and subsequently the piston closes the port 13 of one by-pass, and a maximum resistance is offered to the piston in order that the disks of the clutch will be brought gradually into complete engagement. During the retarding action of the dash pot, the shiftable toothed parts of the 50 55 transmission gearing will have been brought into complete engagement before the clutch disks have been completely engaged.
- This retarding device is particularly advantageous in that stuffing boxes for the piston rods and other parts usually extending to the outside of a piston chamber are eliminated, and further in that adjustment of the valve controlling the by-pass is readily effected.

What I claim is:

1. In a retarding device and in combination, a body having therein a cylindrical piston chamber, a by-pass at one side of said chamber extending parallel therewith for a portion of its length and communicating at one end with the bottom of the chamber and at its other end with a portion of the chamber above the piston, the body also having a lateral recess at one side of the upper portion of the chamber, said recess opening into the chamber through a narrow slot, and a second by-pass communicating at one end with said recess and opening at its opposite end into the piston chamber a distance from the position reached by the lower face of the piston at the end of its downward stroke, a piston in the chamber, a rock shaft journaled in the body and extending across the recess, an arm secured at one end to said rock shaft, a link between the other end of the arm and the piston, and means for rocking the rock shaft, substantially as and for the purpose specified.
2. A retarding device comprising a body formed with a piston chamber, and with a recess at one side of one end of the chamber, walls of the recess diverging toward the chamber, one of said walls terminating substantially at the top of said end of the chamber, and said recess having a slot-like entrance into the chamber extending lengthwise thereof from substantially said top, a piston movable in the other end of the chamber, the body being also formed with a by-pass extending lengthwise of the chamber and having its lower end opening into the lower end of the chamber and its upper end terminating short of the top of the chamber, the body being also formed with an additional by-pass extending lengthwise of the chamber and communicating at its upper end with the lower portion of the recess, and having an opening extending into the chamber between the ends thereof in position to be closed by the piston when between its extreme positions, said body comprising a main shell constituting the bottom and side walls of the chamber and the inclosing walls of the recess and the by-passes, and a removable top plate, the piston being formed with a passage therethrough, a spring-pressed valve for controlling the flow through the passage, said valve being opened by the pressure of the fluid when the piston is moved upwardly, and being closed when the piston is moved downwardly, a rock arm movable in the recess and having its free end extending through the slot-like entrance of the recess into the chamber, an intermediate portion of the rock arm being movable lengthwise of said entrance in an arc materially longer than the diameter of the smaller end of the recess, means for actuating the rock

arm, a link for connecting the piston and the free end of the rock arm, and a valve carried by the top plate and removable therewith, said valve extending through the top plate and having its inner end coacting with the upper end of the first-mentioned by-pass, and its outer end provided with means for adjusting said valve, substantially as and for the purpose specified.

In testimony whereof, I have hereunto signed my name, in the presence of two attesting witnesses, at Syracuse, in the county of Onondaga, in the State of New York, this 17th day of April, 1912.

CLARK W. PARKER.
